UNITED STATES PATENT OFFICE.

HENRY L. DARWOOD, OF PHILADELPHIA, PENNSYLVANIA.

PUMP FOR DRAWING AND MEASURING LIQUID.

No. 928,031.

Specification of Letters Patent.

Patented July 13, 1909.

Application filed February 26, 1909. Serial No. 480,265.

To all whom it may concern:

Be it known that I, HENRY L. DARWOOD, a citizen of the United States, residing at the city of Philadelphia, in the county of Philadelphia and State of Pennsylvania, have invented a new and useful Pump for Drawing and Measuring Liquids, of which the following is a specification.

My invention relates to improvements in pumps for elevating or drawing and measuring all kinds of liquids, and especially alcoholic liquors to be sold over a bar; and the objects of my improvements are to provide a pump for drawing liquid from a barrel or receptacle located below the room in which the pump is located, and to provide the latter with means for indicating the accurate amount of liquid drawn.

My invention will be more fully understood taken in connection with the accompanying drawings forming part hereof, and in which:

Figure 1, is a diagrammatic view showing the location of the pump-head, pump-cylinder, piping, a spear and a barrel into which the latter is inserted. Fig. 2, is a vertical central section through the pump-cylinder, piston and valves in said piston, and also the suction and supply pipes. Fig. 3, is a vertical central section through a spear adapted to be inserted through the bung-hole and into a barrel, and showing two valves. Fig. 4, is a vertical section through the pump-head, showing the means for operating the piston, locking devices for permitting the piston-rod to travel only in one and the same direction until the up- or down-movement of the rod is completed, means for shifting said locking devices at the end of each movement, and means for indicating the number of strokes of the piston. Fig. 5, is a section on the line 5—5 of Fig. 4. Fig. 6, is a section on the line 6—6 of Fig. 4. Fig. 7, is a section on the line 7—7 of Fig. 4. Fig. 8, is a section on the line 8—8 of Fig. 4, and Fig. 9 is a section on the line 9—9 of Fig. 4.

Referring now to the drawings for a further description of my invention, and more particularly to Fig. 1, A is the pump-head or casing, in which the devices for operating and locking the piston-rod b^1 is contained. In one side of the pump-head is formed a hollow shaft a with spout a^1 , through which the liquid from the barrel D is discharged. B is the pump-cylinder with piston b and piston-rod b^1 , and b^2 is a pipe communicating with

the cylinder B and hollow shaft a in the pump-head. b^3 is a pipe secured at one end to the lower end of the pump-cylinder B and at its other end to a flexible metallic tubing b^4 , to which the spear C is attached, and D is a barrel from which the liquid is to be drawn. The spear C is composed of a pipe c , closed at the lower end and provided at this end with a series of holes c^1 to permit the liquid to enter the pipe; at the upper end of the spear is secured a head, in which two tight-fitting metallic check-valves c^3 and c^4 are seated. (Fig. 3).

The pump-cylinder B is of any preferred construction and contains the piston b having seated therein two check-valves b^5 (Fig. 2) and this piston b is operated by the piston-rod b^1 to draw liquid from the barrel D, through the spear C, flexible metallic tubing b^4 , pipe b^3 , cylinder B, pipe b^2 , hollow shaft a and spout a^1 . To actuate the piston-rod b^1 , a gear-rack e is secured to the top of the piston-rod b^1 and is mounted in a guide-way of the pump-head A, (Figs. 1, 4, 5, 6 and 7). A gear-wheel e^1 journaled in the head A meshes with said rack e and is operated by the crank e^2 , which when rotated in the direction as indicated by the arrow in Fig. 4 elevates the rack e , and rotating the same in the opposite direction will force the rack e and piston-rod b^1 downward. In order to accurately measure the quantity of liquid drawn by the pump, it becomes necessary to absolutely control the movement of the piston and its rod, that is to say the piston must travel a certain distance and at the end of this distance it must operate an indicator to show that it did travel the full distance. If the end of this distance is not reached there must be means to prevent a retrograde movement until that certain distance has been traveled, when the indicator will be automatically actuated at the completion of such full stroke of the piston and indicate that a certain amount of liquid has been drawn from the barrel D. I obtain these results by means of two pawls i and i^1 , hinged on a shaft i^2 and a switch-lever i^3 fulcrumed on the same shaft i^2 , which latter is journaled in the head A as shown in Figs. 4 and 7. One of these pawls either i or i^1 is always in engagement with a tooth of the rack e to prevent the movement of the latter in one or the other direction. In the drawing the pawl i is shown in engagement with a tooth of the rack e , and therefore the rack e is permitted to move upward, i. e. it

can only be elevated by turning the crank e^2 in the direction of the arrow shown in Fig. 4.

Just before the rack e attains its highest point, the pin e^3 secured in the side of the 5 rack e engages one end of the switch lever i^3 , and shifts the same so that the other end i^4 of the lever leaves the stop-pin a^4 and contacts with the stop-pin a^5 , which stop-pins are both secured inside the pump-head A.

10 The shifting into this position of the switch-lever i^3 , causes the disengagement of the pawl i from the teeth of the rack e , and the engagement of the pawl i^1 with a tooth of the same rack, so that now the rack can only be 15 moved downward, by rotating the crank e^2 in the opposite direction from that indicated by the arrow in Fig. 4, until the rack reaches its lowermost position, when the pin e^4 near the top of the rack will shift the switch-lever 20 i^3 into the position again as shown in Fig. 4.

The switch-lever i^3 is provided with stops i^5 for the pawls i and i^1 to rest against and a spring i^6 for each pawl tends to keep the latter in position against the stops i^5 . The 25 switch-lever i^3 is held in one or the other position by friction obtained by inserting a spring-washer i^7 between the switch-lever and the walls of the pump-head A.

To indicate or record the number of strokes 30 of the piston b , an indicator of any preferred make or style may be used and operated by the rack e . In Figs. 4, 5, 8 and 9, is shown an indicator and its actuating mechanism, which are found simple and efficient; the 35 indicator o shown is a "Veeder", covered by U. S. Patent No. 548,482, of October 22, 1895, and is actuated by a lug e^5 at the upper end of the rack e , which contacts with the lever o^1 secured to the rock-shaft o^2 journaled 40 in the housing o^3 of the indicator o ; at the other end of the rock shaft o^2 is secured an arm o^4 , to which is hinged a pawl o^5 engaging the teeth of the ratchet-wheel o^6 fastened to the shaft of the indicator o ; a spring o^7 is 45 employed to turn the ratchet-wheel and indicator disks, while the upward movement of the rack e and lug e^5 causes the rocking of the shaft o^2 against the action of the spring o^7 and the engagement of the pawl o^5 with the 50 next tooth of the ratchet-wheel o^6 .

Since the double check-valves in the spear C and piston b prevent any back-flow or leakage, it follows that as each full stroke of the piston draws a certain predetermined quantity of liquid, the amount of liquid drawn from the barrel can be ascertained with accuracy from the indicator o at any time, through the sight-hole a^2 of the pump-head A.

Having thus described the nature and objects of my invention, what I claim as new and desire to secure by Letters Patent is:

1. In a pump for drawing and measuring liquid the combination of the piston-rod and its operating devices, with means for locking 60 the rod against retrograde movement while moving in either direction, until the limit of the travel of the rod has been reached, means for switching the means for locking the rod when the latter moves in the opposite direction, and an indicator to indicate the number of strokes of the said rod, substantially as and for the purposes set forth.

2. In a pump for drawing and measuring liquid the combination of the piston-rod and 75 its operating devices, a rack formed on the piston-rod, a set of pawls, a switch-lever for said pawls, means for operating said switch-lever, and an indicator for indicating the 80 number of strokes of the piston-rod, substantially as and for the purposes set forth.

3. In a pump for the purpose described the combination of the piston-rod and its operating devices, a rack attached to said piston-rod, a gear-wheel meshing with said rack and 85 adapted to operate the same, a set of pawls, a switch lever controlling said pawls and actuated by pins on said rack to prevent the movement of the rack in a direction opposite to that in which the gear-wheel forces the 90 said rack, and an indicator adapted to be automatically operated by said rack, substantially as and for the purposes set forth.

In witness whereof I have hereunto set my hand in the presence of two subscribing witnesses.

HENRY L. DARWOOD.
